Primary Examiner — John Windmuller*Assistant Examiner* — Steven J Czyz(74) *Attorney, Agent, or Firm* — Justin W. McCabe;
Dunkiel Saunders Elliott Raubvogel & Hand PLLC(57) **CLAIM**

The ornamental design for a fluid container, as shown and described.

DESCRIPTION

FIG. 1 is a perspective view of a fluid container;
FIG. 2 is a perspective view of the fluid container of FIG. 1, and shown in use;
FIG. 3 is a front plan view thereof;
FIG. 4 is a rear plan view thereof;
FIG. 5 is a right side plan view thereof;
FIG. 6 is a left side plan view thereof;
FIG. 7 is a top plan view thereof;
FIG. 8 is a bottom plan view thereof;
FIG. 9 is a perspective view of the fluid container with the internal bladder removed; and,
FIG. 10 is a perspective view of the fluid container with the unclaimed bladder port on the opposite side for ease of disclosure.
The broken lines depict portions of the article and environment that form no part of the claimed design.
